(57) **CLAIM**

The ornamental design for an asymmetrical hinge plate adapter, as shown and described.

DESCRIPTION

FIG. 1 is an upper front perspective view of the asymmetrical hinge plate adapter showing my new design;

FIG. 2 is a lower back perspective view of the asymmetrical hinge plate adapter showing my new design;

FIG. 3 is a top view of the asymmetrical hinge plate adapter;
FIG. 4 is a bottom view of the asymmetrical hinge plate adapter;

FIG. 5 is a left view of the asymmetrical hinge plate adapter;
FIG. 6 is a right view of the asymmetrical hinge plate adapter;

FIG. 7 is a front view of the asymmetrical hinge plate adapter;

FIG. 8 is a back view of the asymmetrical hinge plate adapter;

FIG. 9 is a perspective view of the asymmetrical hinge plate adapter shown reduced in scale and installed on an exemplary guitar; and,

FIG. 10 is a bottom view thereof.

The asymmetrical hinge plate adaptor is shown in an environment of use, the broken lines forming no part of the claim.

1 Claim, 5 Drawing Sheets
